Primary Examiner — Susan Bennett Hattan*Assistant Examiner* — Omeed Agilee(74) *Attorney, Agent, or Firm* — Schiff Hardin LLP(57) **CLAIM**

The ornamental design for a patient table, as shown and described.

DESCRIPTION

FIG. 1 is a front view of a patient table showing our new design;

FIG. 2 is a back elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a top back right perspective view thereof;

FIG. 8 is a top front left perspective view thereof; and,

FIG. 9 is a top front left perspective view thereof in an alternative position.

The broken lines shown in the drawings depict portions of the patient table that form no part of the claimed design.
